UNITED STATES PATENT OFFICE.

SAMUEL B. HUNTER, OF TACOMA, WASHINGTON.

MONEY-CHANGING MACHINE.

Application filed April 12, 1922. Serial No. 551,879.

To all whom it may concern:

Be it known that I, SAMUEL B. HUNTER, a citizen of the United States of America, residing at Tacoma, in the county of Pierce, 5 and State of Washington, have invented certain new and useful Improvements in Money-Changing Machines, of which the following is a specification.

This invention relates to an improvement 10 in money changing machines, wherein thru the operation of one or more appropriately marked keys, a coin or coins, corresponding to the amount of change desired in the particular transaction, may be delivered to the 15 customer.

The present machine embodies the general features of a plurality of coin receptacles, in which the several coins of different denominations, are arranged in piles of superimposed relation, a coin slide being provided for each receptacle and adapted to be actuated by the depression of a particular key. The coin slide of the present invention 20 is so formed as to impart a tilting movement to the coin engaged and moved by said slide, the coin chute or way which receives the coin from the slide being formed to positively wipe the coin off the slide, to materially facilitate and positively insure 25 the delivery of that coin to the change tray.

The invention is illustrated in the accompanying drawings, in which:—

Fig. 1 is a broken plan of the improved machine.

35 Fig. 2 is a section on line 2—2 of Fig. 1.

Fig. 3 is a section on line 3—3 of Fig. 1.

Fig. 4 is a broken front elevation of the machine.

40 Fig. 5 is a perspective view of one of the slides.

The improved machine comprises a block 1, mounted upon a base 2, which may and preferably is formed to slidably receive a coin drawer 3. The base 2 in advance of 45 the block 1, is formed for the reception of the operating parts, and is preferably inclosed in a metallic ornamental cover 4.

The block 1 is formed with a series of vertical bores 5, respectively corresponding 50 in size to that of the coins for which the machine may be designed; that is, these bores constitute coin receptacles in which the coins are arranged in superimposed relation, to provide a series of columns of coins of varying values. The bottom of the

block 1 is formed with a transverse channel 6, of less width than the diameter of the particular coin receptacle, and slidably mounted in each of these channels 6, is a coin slide 7. A coin chute 8 also communicates with each coin receptacle, this chute opening from the bottom of the particular coin receptacle and thru the forward wall of the block 1, and the delivery end of the chutes discharging into a coin tray 9. As 60 will be plain from Fig. 3 of the drawing, these chutes 8 incline downwardly toward the coin tray, their inner ends terminating substantially on a plane with the upper coin receiving surface of the slide 7. The side 70 walls of the chutes 8 incline or curve laterally, one of such walls as 9 being interposed in the path of the coin on the coin slide as the latter is operated. The coin receiving surface of the coin slide, indicated at 10, 75 Fig. 5, inclines laterally or toward the delivery end of the coin chute, this surface 10 being so formed as to present an abrupt or coin-pushing shoulder 11 in the slide.

As stated, the respective coin receptacles 80 are designed to hold coins of various sizes, and a series of operating keys 12 are provided, one for each receptacle. These keys are independently mounted upon a shaft 13 secured within the space closed by the cover 4, and are each formed with a sector-shaped projection 14, formed with an interior series of gear teeth 15, adapted to engage and operate a pinion 16, loosely supported upon a shaft 17 mounted in the casing. A gear 18 85 is fixed with relation to the pinion 17, the teeth of this gear cooperating with a rack 19 on the immediately adjacent coin slide 7. A spring 20 serves to normally hold the parts in such relative positions that the coin receiving space 10 of each slide bar 7 is positioned immediately beneath the lowermost coin in each coin receptacle. 95

On desiring change, such for example, as thirty-five cents, the operator will depress 100 the keys, corresponding for example, with the coin receptacles containing the quarters and dimes, the keys of course being suitably marked at 21 to indicate the value of the coins which they control. Thru obvious 105 movement of the sectors and gears, the corresponding coin slides 7 will be moved forwardly, the shoulders 11 engaging the lowermost coins and carrying the same forwardly until the coins are intercepted by the 110

walls 9 of the corresponding coin chutes, whereupon owing to the curved formations of these walls, and the corresponding inclinations of the coin slides receiving surfaces 5 10, the coins are deflected into the coin chutes and so delivered to the coin tray.

Thus, with an appropriate number of coin receptacles, any desired aggregate amount of change can be instantly delivered to the 10 customer merely thru the operation of the appropriate keys.

An important detail of the present invention is the provision of a coin slide of materially less width than the coin receptacle, 15 that is, the coin, so that the coin is merely supported on said slide and even in this support is inclined in the direction of its discharge in the coin chute. The narrow coin slide thus permits ready deflection of the 20 coin into the coin chute by the curved wall of the latter, thus materially simplifying the construction of the apparatus while insuring its certainty of operation.

Claims:

1. A change making apparatus, including 25 a coin receptacle, a coin slide operatively positioned to eject the bottom coin from said receptacle, means for operating the slide, said slide having a laterally inclined coin receiving surface, and a coin chute positioned beyond the receptacle and having a wall formed to direct the coin from said slide into the chute.

2. A change making apparatus, including 35 a coin receptacle, a coin slide operatively positioned to eject the bottom coin from said receptacle, said slide having a coin receiving surface of materially less width than the diameter of the coin and laterally inclined, a coin chute formed beyond the receptacle 40 and having a wall curved across the path of movement of the coin on the slide, whereby to deflect said coin from the slide into said chute.

In testimony whereof I affix my signature.

SAMUEL B. HUNTER.
